UNITED STATES PATENT OFFICE.

THOMAS J. BROWN, OF WASHINGTON, DISTRICT OF COLUMBIA.

SHINGLE.

Application filed October 20, 1923. Serial No. 669,865.

To all whom it may concern:

Be it known that I, THOMAS J. BROWN, a citizen of the United States, residing at Washington, in the District of Columbia, 5 have invented certain new and useful Improvements in Shingles, of which the following is a specification.

The present invention relates to roofing shingles of the composite type, and one of 10 the primary objects is to provide a shingle that is reversible and so constructed that when laid one way it is an individual shingle and when reversed and laid in the opposite direction, constitutes a multiple or so-called 15 "strip" shingle. A further and important object is to provide a shingle of this character that will produce a relatively thick roof by overlapping to an extent to form a three-layer covering, constituting sub- 20 stantially ninety-five percent of the roof area, a portion being four layers thick, and a very small amount two layers. A still further object is to provide a shingle that may be cut from a sheet with a minimum 25 amount of waste, and so cut that when the shingles are laid a variegated and therefore pleasing appearance will be given to the roof.

The preferred embodiment of the invention 30 is illustrated in the accompanying drawings, wherein:—

Figure 1 is a plan view of the shingle,

Figure 2 is a plan view showing a series 35 of said shingles laid with the individual butts exposed,

Figures 3 and 4 are respectively sectional views taken on the lines 3—3 and 4—4 of Figure 2,

Figure 5 is a plan view of the shingle 40 reversed,

Figure 6 is a plan view of a set of shingles laid with the multiple butts exposed,

Figures 7 and 8 are sectional views respectively on the lines 7—7 and 8—8 of Figure 6,

Figure 9 is a plan view illustrating a strip 45 and a method that may be employed for cutting the shingles therefrom.

The shingles are preferably made of flexible water-proof material of the well-known 50 kind, and their outer surfaces are coated with slate or other fire-proof substance embedded in the body of the material. As disclosed, each shingle consists of a rectangular body 10, preferably about twice as 55 wide as it is long. Projecting from one of the end edges of the body 10, and centrally

thereof, is a single exposure butt 11, preferably semi-hexagonal, though the form thereof may be varied. Projecting from the opposite edge of the body 10 are a plurality of 60 exposure butts 12 that are preferably, though not necessarily, square and are divided by a central slot 13. The sides are also cut away to form slots 14 half the width of the central slot 13. While the sizes of the 65 body and butts may be altered, it has been found that the following proportions are very satisfactory for covering purposes, as well as appearance. The body can be 8 by 16 inches; the length of the butts 11 and 12 70 may be 4 inches; the width of the butt 11 at its juncture with the body may be 10 inches, while the widths of the square butts 12 may be $7\frac{1}{2}$ inches. The butts 12 will be individually of less area than the butt 11. 75

The shingle, as above produced, may be laid with either the butts 11 or the butts 12 to the weather. In the former case, and as illustrated in Figure 2, when so laid, it will be noticed that a hexagonal appearance will 80 be given to the roof. Further than this the area of the roof is very completely and thoroughly protected. A portion thereof, as will be clear by reference to Figures 3 and 4, has four thicknesses of shingles, and the 85 greater portion approximating ninety-five per cent, has three thicknesses. Thus, not only is there practically no chance of rain driving inwardly beyond the shingles, but the roof has long-wearing qualities. In 90 order to illustrate this as clearly as possible, it will be noted that at the left of Figure 2, the different layers of shingles are indicated differently. Thus the uppermost layer is shown in full lines, the second layer in dash 95 lines, the third layer in dash and dot lines, and the fourth layer in dotted lines. The shingles may also be reversed and laid with the square butts to the weather, as indicated in Figures 6—8 inclusive. When so laid the 100 same effective covering is provided. Furthermore the exposed butts which are subjected to the most severe conditions are the elements that are underlaid the thickest.

In addition to the protective covering 105 provided and the different designs that are available, it materially reduces the amount of stock that a dealer must carry or a purchaser may buy, inasmuch as the one structure produces both an individual and a strip 110 shingle. Furthermore, as indicated in Figure 9 the shingles can be produced with a

minimum amount of waste, the only loss being that required to produce the slots 13 and 14. As shown in said figure, the lines of shingles are cut lengthwise of the sheet 5 and the butts 11 of one row produce the spaces between the butts of the adjacent rows. It will also be noted that these rows are thus cut oppositely to each other, and that the shingles are reversely arranged.

10 One of the outstanding features of this shingle is due to this method of cutting. Owing to the texture of the slate granules with which this type of material is surfaced and their relation on the surface, light reflections of different hues are cast from different angles. As a consequence where shingles or units are all cut and laid on a roof so that each and every unit lays the same as before being cut, the light reflections are always the same. Because of the present method of cutting the shingles, when they are reversed and applied on the roof, a variegated or mottled effect is brought out regardless of which design is used, either 20 the hexangular or rectangular.

15 From the foregoing, it is thought that the construction, operation and many advantages of the herein described invention will be apparent to those skilled in the art, 30 without further description, and it will be understood that various changes in the size, shape, proportion and minor details of construction may be resorted to without departing from the spirit or sacrificing any of the 35 advantages of the invention.

What I claim as new, is:—

1. A shingle comprising a body having a single exposure tab projecting from one

end and a plurality of exposure tabs projecting from the opposite end. 40

2. A shingle comprising a body having a single exposure tab projecting from one end and terminating short of its sides, and a plurality of exposure tabs projecting from the opposite end and having the interstices 45 between them in line with the opposite single tab.

3. A shingle comprising a body having a single exposure tab projecting centrally from one end edge and terminating short 50 of the side edges thereof at its juncture with the body, and a plurality of tabs projecting from the opposite end edge of the body and shaped differently from the single tab.

4. A shingle comprising a body having a single semi-hexagonal tab projecting centrally from one end edge and terminating short 55 of the side edges thereof at its juncture with the body, and a plurality of square butt tabs projecting from the opposite end 60 edge of the body and shaped differently to the single tab.

5. A shingle comprising a body having a single exposure butt on one end and a plurality of butts projecting from its opposite 65 end, the length of each butt being substantially one-half the width of the body.

6. A shingle comprising a body having exposure units projecting from its opposite edges, there being a greater number of such 70 units on one end than the other and said latter units being individually of less area and all of equal size and shape.

In testimony whereof, I affix my signature.

THOMAS J. BROWN.
